UNITED STATES PATENT OFFICE.

WILLIAM J. PETER, OF NEW YORK, N. Y.

CHARGING MEANS FOR OIL TANKS.

Application filed March 27, 1925. Serial No. 18,783.

To all whom it may concern:

Be it known that I, WILLIAM J. PETER, a citizen of the United States, residing at New York city, in the county of Bronx, State of New York, have invented certain new and useful Improvements in Charging Means for Oil Tanks; and I do hereby declare the following to be a full, clear, and exact description of the invention, such as will enable others skilled in the art to which it appertains to make and use the same.

This invention relates to hydraulic systems for storing, handling and delivering oil, and more particularly to means for filling such systems with oil and automatically controlling the quantity of oil introduced.

In hydraulic systems for storing, handling and delivering oil, the storage tank is always filled with liquid, oil and water, the oil overlying the water. In dispensing, the oil is forced out through a pipe in the top of the tank by forcing water in through the bottom. In filling the tank with oil the pressure is reversed, the oil being forced in through the top of the tank and the water out through the bottom and to waste. In order to prevent oil from following the water into the drain some means must be provided, either for indicating that the tank has been filled, or for automatically arresting the flow.

It has been proposed to place a float valve in the water discharge pipe at the bottom of the tank, designed to close automatically when oil passes. With such a valve, however, a certain amount of oil must always pass into the drain before the valve can close and moreover, a valve situated at the bottom of the tank is inaccessible and cannot be easily reached for repairs or adjustment. Various means have also been proposed for automatically closing the oil inlet valve when the tank has been filled but none of these has proved successful, and none so far as I am aware is in commercial use.

It is the object of the present invention to provide means which shall positively and automatically shut off the flow of oil to the tank when the tank is filled without waste of oil and without attention on the part of the operator. I have attained this object by placing a valve in the oil intake pipe normally lying out of the path of flow, and operated by means of a float situated near the bottom of the tank designed to float in water but sink in oil the entire control

mechanism being situated wholly within the tank. When during the filling operation the oil level reaches this float, it sinks, moves the valve into the path of flow and seats it, thus shutting off further influx of oil. Later during the delivery of the oil in normal operation the oil level rises and the float, moving upward, opens the valve. In order to prevent the oil being forced out through the intake, I place a check valve within it, although the same result could be attained by forcibly holding the valve closed until time for refilling.

In order that the invention may be more clearly understood, I have illustrated a preferred embodiment of it in the accompanying drawing, in which Figure 1 is a diagrammatic elevation of a hydraulic oil storing and delivering system equipped with the automatic filling control valve of the present invention. Figure 2 is an enlarged vertical section through the control valve showing the valve in open position, and Figure 3 is a vertical section similar to Figure 2, but taken at right-angles to the latter and showing the valve closed.

Referring first to Figure 1, the storage tank is indicated by reference numeral 1. This is the ordinary cylindrical storage tank used in most systems and is commonly placed within an excavation with its longitudinal axis horizontal. The oil is introduced through a pipe 2 equipped with a filling plug 14 and discharged through a riser 3 having a valve 4 both entering the top of the tank as indicated, while the water is introduced and discharged through a pipe 5 which enters the tank at the bottom. In the system illustrated the water pressure is obtained by maintaining a constant head in the riser 6 which is connected with the pipe 5 through a valve 7. The upper end of the riser 6 terminates in a float box 8 into which water is fed from any convenient source, such as the city water mains, through a feeder pipe 9, the level of the water in the float box being automatically maintained constant by means of a float valve 10. A valve 11 placed between the pipe 5 and the drain 12 controls the connection between the tank and the drain. Valves 7 and 11 are preferably operated simultaneously by means of a valve rod 13 and the connections are so designed that when valve 7 is opened, valve 11 is closed, and vice-versa.

The system just described is commonly

- known as a constant head hydraulic system and, of itself, forms no part of the present invention. I shall, however, describe briefly the manner in which this system operates.
- 5 During the filling of the tank, valve 7 is closed and valve 11 opened, thus connecting the water pipe 5 with the drain 12. Oil is then forced into the pipe 2 and forces the water out through the pipe 5 to the drain.
- 10 During delivery of oil the valve 7 is opened and the valve 11 closed so that the pressure of the constant head maintained in riser 6 by the float valve 10 forces oil up the riser 3 and out. When the tank is not in actual
- 15 use, valve 7 is preferably closed and valve 11 opened so that the tank is not under pressure. The valve 4 thus acts merely as a locking means and does not necessarily form a part of the operating mechanism.
- 20 The present invention relates to the intake control valve and its attendant mechanism which I shall now describe in detail. The oil is introduced into the tank 1 through the pipe 2 after removing the filling plug 14
- 25 and attaching a hose from a tank wagon or other source of supply. From the pipe 2 the oil passes through a valve housing 15 integral with a man-hole cover 20, through an intake aperture 16 and into the tank.
- 30 Mounted within the valve housing 15 is a valve 17 adapted, when closed, to be seated upon a valve seat 18 surrounding the intake aperture 16. The valve is provided, on its upper face, with an integral guide
- 35 pin 19 which moves within a guideway 21 in a cap 22 which is threadedly mounted upon the valve housing 15. The upper end of this cap is provided with an air relief pipe 23 controlled by means of a valve 24.
- 40 The valve when open lies out of the path of flow as illustrated in Figure 2.

The valve 17 is operated by means of a float 25 pivotally mounted near the bottom of the tank upon a vertical angle bar 26 depending from the man-hole cover 20. The float 25 and the valve 17 are operatively connected by means of the float stem 27, pivoted upon the angle 26 at 28, a vertical connecting rod 29, a pivoted arm 31 and a link 32. The float 25 is designed to float in water and sink in oil, so that the position of the valve 17 is determined by the position of the oil and water level. Within the pipe 2 and just beyond the valve housing 15 is a check valve 33 which effectively prevents outward flow of oil through the pipe 2.

The intake control valve functions as follows: When the tank has been emptied of oil (being then substantially filled with water) and a fresh supply is to be added, the filling plug 14 is removed and the supply hose attached to the intake pipe 2. As the tank is now filled with water it is obvious

60 that float 25 will be in its uppermost posi-

tion and the valve 17 raised to permit the inflow of oil. Oil is then forced through the intake, opening the check valve 33, and forcing the water in the tank out through the pipe 5 and through the drain 12, the valve 11 having been previously opened as explained above. When the oil and water level reaches the float 25, the float follows the oil down and automatically seats the valve 17 by moving it into the path of flow before the oil level reaches the water outlet, absolutely preventing further influx of oil. There is therefore no overflow at the filling plug and no oil passes through the drain and to waste. As soon as the direction of flow is reversed for delivery purposes, water being forced in through pipe 5 and oil out through the oil discharge pipe 3, the float 25 rises with the rising oil and water level and opens the valve 17, the check valve 33 then preventing outflow of oil through the intake. The valve 17 is thus in readiness for refilling when the time comes.

The valve operating mechanism including the float is placed wholly within the tank so that there is no necessity for stuffing boxes, which, in order to remain leak-proof under the operating pressure, would have to be so tight that the float, acting only on the slight differential buoyancy between oil and water, could not function efficiently. By stating that the valve control mechanism is situated wholly within the tank I do not mean that the immediate connection with the valve necessarily lies within the tank. It is clear that the valve housing 15 might be made considerably longer so that the link 32 would extend beyond the upper wall of the tank. Its position would, nevertheless, be effectively within the tank and always immersed within the liquid in the tank.

In the interest of clearness, I have illustrated the filling control valve of the present invention installed in connection with a constant head delivery system. There is, however, no essential relation between the means for applying the pressure and the filling mechanism, and the latter could be used in systems equipped with other pressure applying means, such for example, as the one disclosed in my co-pending application, Serial No. 18,782 filed concurrently here-

130

As illustrated in Figures 2 and 3, I preferably make the valve housing integral with the man-hole cover 20 which is designed to fit the standard man-hole on tanks of this character. The float supporting angle 26 is also mounted upon the lower face of this man-hole cover so that the entire valve and its operating mechanism can be installed and removed as a unit.

I claim:

1. In a hydraulic oil storage and delivery system in which oil is delivered through an

oil discharge pipe near the top of a tank by means of water forced in near the bottom, the combination of an oil intake near the top of the tank, a water discharge near 5 the bottom of the tank, a valve in the intake, a float near the bottom of the tank designed to float in water and sink in oil, a system of levers within the tank connecting the float and the valve so that when during 10 filling of the tank with oil the oil level reaches the float the valve is closed and when during delivery of oil the oil level passes above the float, the float acting through a system of levers opens the valve, 15 and a check valve in the intake preventing outflow of oil through the intake during delivery of oil.

2. In a hydraulic oil storage and delivery system, the combination of a tank, an oil intake near the top of the tank, a water discharge near the bottom of the tank, a valve in the intake, a bar depending from the top of the tank to a point adjacent the bottom, a float designed to float in water and sink in oil, a stem on the float pivotally mounted 20 upon the bar near the bottom of the tank, an arm pivotally mounted near the top of the bar, means connecting one end of the arm with the valve, and means connecting the other end of the arm with the float stem, the 25 parts being so arranged that when the oil level reaches the float the valve is closed.

In testimony whereof I affix my signature.
WILLIAM J. PETER.
